UNITED STATES PATENT OFFICE

2,502,093

METAL WAGON BODY

William D. Johnson, Streator, Ill.

Application September 23, 1946, Serial No. 698,613

3 Claims. (Cl. 296—28)

1

This invention relates to farm wagon bodies, and its principal object is to provide an all metal wagon body of substantial construction capable of many uses.

Another object is to provide a wagon body of metal stampings which are easily assembled and fastened together, either by bolts and nuts or rivets, or they may be welded together.

Another object is to provide a wagon body which is grain tight, and having a tail gate, which makes a grain tight joint with the body.

Another object is to provide a tail gate arranged to be pivotally connected to the body at its upper or lower edges by novel connecting means.

Other objects and advantages will appear in the course of the following specification, and with said objects and advantages in view, this invention consists in the several novel features of construction, arrangement and combination of parts hereinafter fully described and more particularly defined in the appended claims.

The invention is clearly illustrated in the accompanying drawings, in which:

Fig. 1 is a perspective view of a metal wagon body embodying a simple form of the present invention;

Fig. 2 is a vertical cross-section thereof taken substantially along the line 2—2 of Fig. 1;

Fig. 3 is a view, partly in plan and partly in horizontal section, partly broken away, taken on the line 3—3 of Fig. 2;

Fig. 4 is a vertical longitudinal section, partly broken away;

Fig. 5 is a vertical section taken on the line 5—5 of Fig. 3;

Fig. 6 is a vertical section taken on the line 6—6 of Fig. 3; and

Fig. 7 is a perspective view of the tail gate.

Referring to said drawings, which are merely illustrative of a simple embodiment of the invention, the reference character 10 designates the bed of the wagon body, from the side edges of which rise the side walls 11, which are connected at the front end of the body by a front end wall 12 which rises from the front edge of the bed. Narrow rear end walls 13 extend up from the rear edge of the bed and join the side walls. A discharge opening is left between the rear end walls. In the discharge opening be-

2

tween the walls 13 is a tail gate 14 for closing the discharge opening. A relatively heavy angle bar 42 extends along the rear edge of the bed and is riveted or otherwise rigidly secured thereto.

The bed of the wagon is composed of sheet metal non-sagging channel members 15, which extend crosswise of the bed, with their vertical webs 16 bolted, riveted or otherwise rigidly fastened together. The channel members 15 are brought into a state of tension by drawing up the bolts. To make grain tight joints between the channel members, strips of Masonite 17, or other non-metallic strips, may be interposed between the vertical webs of the channel members to provide leak proof joints. The non-metallic strips result in evenness of the channel members by drawing up the bolts that connect them. They also reduce the noise caused by metal against metal.

The channel members 15 are formed with flanges 15^a, which rest upon and are bolted or otherwise rigidly fastened to two longitudinally extending sills 18, here shown as composed of I beam formation, or they may be of channel formation; and said sills rest upon and are rigidly fastened to girders 19 (see Fig. 4), here shown as of channel formation. The girders 19 are carried by the running gear of the wagon.

The rear ends of the sills are preferably beveled as shown, to permit the body to be tilted in dumping into grain hoppers of elevators.

The side walls are each composed of a sheet of sheet metal struck up with suitable dies to give them the reinforced construction shown. The lower portion of each side wall has a sloping brace portion 20 secured thereto, which terminates in a vertical U bent flange 21 that extends along the side edge of the wagon bed, and terminates in a horizontal flange 22 that rests on the wagon bed. The lower end of each side wall is flanged as at 11^a and rests on the flange 22 of the brace 20. The flanges 11^a, 22 are bolted, riveted or otherwise rigidly secured to the bed. Toward the upper edge of each side wall, the metal is struck up outwardly along lines extending lengthwise of the side wall to provide one or more reinforcement ribs 23, and the upper edge portion of each side wall is folded outwardly and back to provide a wide rail 24, which may

terminate in a downturned flange 25 to stiffen the rail. This horizontal bracing does away with vertical braces that require much welding.

It is to be observed that the horizontal reinforcement ribs provide very substantial reinforced side walls that are not likely to buckle due to pressure of the contents against them.

The front end wall 12 is also formed of a sheet of struck up sheet metal, flanged at the bottom and bolted, riveted or otherwise fastened to the bed. Its side edges are joined to the side walls, and its upper edge may be formed with a rail like the side walls. The front end wall may be provided with struck up upright ribs for the purpose of stiffness.

The lower ends of the rear end walls 13 are flanged, and bolted, riveted or otherwise rigidly fastened to the bed, and the outer side edges of the rear end walls are flanged as at 27 to obtain stiffness and rigidity, and the adjacent rear edges of the side walls are flanged and bolted, riveted or otherwise rigidly secured to the rear end walls. Diagonally extending flanged sheets 28 extend across the inner corners of the body, and are secured to the side walls and rear end walls.

To the rear end walls 13 are welded U shaped brackets 30 at places adjacent the inner edges of the rear end walls at the tops and bottoms of said walls, and the tail gate 14 is provided with round rods 31, 32, one at the top of the gate and one at the bottom thereof, arranged to be engaged in the crotches of the U brackets 30 and removably held therein by cotter pins 33, 34, adapted to be inserted into eyes in the forks of the U brackets, located in front of the spaces occupied by the rods. With the cotter pins inserted into the eyes, the rods cannot be disconnected from the U brackets, and the tail gate may tilt upon the upper or lower U brackets as fulcrums. The tail gate 14 constitutes an inexpensive scoop board or plate. The upper edge of the tail gate is folded around the upper rods as at 35, and to the lower edge of the tail gate is riveted or welded a flanged stripe 36, which is folded around the lower rod. The rods are welded or otherwise rigidly secured to the folded over flanges.

To each pin 33, 34 is fastened one end of a chain 37 or 38, which extends to a rod 31 or 32, and is welded or otherwise fastened thereto. The chains which are fastened to the rod 31, located at the top of the tail gate, lead to the pins 33, and the chains which are fastened to the rod at the bottom of the tail gate lead to the pins 34, which are associated with the lowermost U brackets. By withdrawing the uppermost pins 33, the gate may be tilted outwardly on the lower U brackets, and by reinserting the pins 33, the tail gate will be held in open position by the chains. With the tail gate connected to the rear end walls by the rods, pins and U brackets, the lower pins 34 may be withdrawn from the associated U brackets, and the tail gate permitted to swing outward on the upper brackets as a fulcrum, and by reinserting the pins 34 in the lower U brackets, the outward swing of the tail gate is limited by the chains 38.

The tail gate fits between the inner side edges of the rear end walls 13, as seen in Fig. 3, and makes grain tight joints therewith. The inner edge of each rear end wall is flanged outwardly as at 39 (see Fig. 33), and each side edge of the tail gate is provided with a U-shaped flange 40, arranged to overlap the flanges 39 on the rear end walls to provide the grain tight joints.

The tail gate 14 is formed with an opening 14a, through which grain, soy beans and the like may

be discharged. Normally the opening is closed by a vertically sliding dump gate 43, the side edges of which are guided in ways 44b, located between the tail gate and flanges 44a of upright angle iron bars 44 that are welded or otherwise secured to the tail gate. When closed the lower edge of the dump gate rests on the flanged strip 36 of the tail gate and makes a grain tight joint therewith.

Means are provided for raising and lowering the dump gate. As shown, said raising and lowering means comprises a U-shaped lever 45, having out-turned upper extremities 46, which are pivotally mounted in brackets 47 welded or otherwise secured to the angle iron bars 44. Midway between the ends of the arms 48 of the lever 45, said arms are offset as at 49, and upon said offset portions links 50 are pivoted thereto, their lower ends being pivoted to the dump gate or angle iron bars 51, welded or otherwise secured thereto. A clip 52 pivotally secured to the tail gate may be swung over the horizontal bar of the lever 45 to positively hold it in its down position with the dump gate closed. The angle iron bars 44 are each provided with several holes 53, and the angle iron bars 51 are each provided with a hole 54, through which bolts or pins 55 may be passed to hold the dump gate in several raised positions.

The dump gate is raised by releasing the lever 45 from the clip 52, and swinging it upward to the desired place, and the bolts or pins 55 are then inserted into the registering holes in the angle iron bars 44, 51.

To the inner face of the tail gate, adjacent its side edges, are fastened wings 41 that serve as braces for fastening thereto larger wings to prevent overflow of grain.

Having thus described my invention, it is obvious that various immaterial modifications may be made in the same without departing from the spirit of my invention; hence, I do not wish to be understood as limiting myself to the exact form, construction, arrangement and combination of parts herein shown and described, or uses mentioned.

What I claim as new and desire to secure by Letters Patent is:

1. In a metal wagon body, and in combination, a wagon bed composed of secured together channel members, with their main webs placed uppermost, sills secured to and supporting said channel members, and side walls, each composed of a metal sheet having a flange on its lower edge secured to the wagon bed, said metal sheet being formed between its upper and lower edges with one or more reinforcement ribs, and being formed at its upper edge with an outwardly directed rail, and a pair of struts, each in the form of an elongated, longitudinally extending metal sheet having its upper edge spaced upwardly from said bed and secured to one of said side wall sheets, said strut extending downwardly and outwardly to adjacent the side edge of the bed and terminating in an inwardly extending horizontal flange rigidly secured to the bed.

2. In a metal wagon body, a side wall composed of a metal sheet having a flange on its lower edge secured to the wagon bed, said metal sheet being formed between its upper and lower edges, with one or more reinforcement ribs, and being formed at its upper edge with an outwardly directed rail, and a sloping strut in the form of an elongated metal sheet extending substantially the length of said side wall and having its upper edge spaced upwardly from said bed and secured to

the side wall sheet, said strut extending downwardly and outwardly to adjacent the side edge of the bed and terminating in a flange rigidly secured to the bed.

3. In a metal wagon body, a bed, side walls rising therefrom, spaced narrow rear end walls secured to said bed and side walls and providing a discharge opening between such end walls, and corner members positioned within said body and extending upwardly from said bed and diagonally across the corners between the side walls and rear end walls with the side edges of each corner member extending to the respective side and end walls forming the adjacent corner, permitting even flow of grain through the discharge opening between the rear end walls.

WILLIAM D. JOHNSON.
